UNITED STATES PATENT OFFICE.

EDWIN E. BARNEY, OF NEWARK, NEW JERSEY, ASSIGNOR TO REMINGTON TYPE-WRITER COMPANY, OF ILION, NEW YORK, A CORPORATION OF NEW YORK.

TYPEWRITING MACHINE.

Application filed March 10, 1920. Serial No. 364,644.

To all whom it may concern:

Be it known that I, EDWIN E. BARNEY, citizen of the United States, and resident of Newark, in the county of Essex and State 5 of New Jersey, have invented certain new and useful Improvements in Typewriting Machines, of which the following is a specification.

My invention relates to typewriting machines and more particularly to the main spring and associated parts for propelling the carriage.

Among the objects of my invention are to make the main spring assembly as a detachable unit; to provide a construction whereby the said unit can be removed from the machine without losing the tension of the main spring; to provide a construction whereby in case of breakage or slipping of 20 the tape the spring will be automatically locked against unwinding; to provide an easy and positive means for attaching the main spring to its box or drum in such a way that it can be very readily and easily 25 removed and replaced with a new one; to provide a construction in which the winding up of the spring to put it under tension is very simple and easy; to provide a long bearing for the main shaft; and generally 30 to provide a simple, good and efficient construction and one easily assembled and taken apart for repairs.

To the above and other ends my invention consists in certain features of construction 35 and combinations and arrangements of parts all of which will be fully set forth herein and particularly pointed out in the claims.

In the accompanying drawings in which my invention is illustrated,

40 Figure 1 is a rear elevation of the band wheel and some of the associated parts, some parts being shown in section on the line $x-x$ of Fig. 3.

Figure 2 is a front elevation of the spring 45 drum or box and some of its associated parts, parts being shown in section on the line $y-y$ of Fig. 3.

Figure 3 is a front to rear vertical sectional view through the axis of the spring 50 shaft and showing fragments of the frame and carriage of the typewriter.

Figure 4 is a perspective view from the rear of the spring drum or box and the spring cage, the latter shown removed from 55 the box.

Figure 5 is a perspective view of a collar for the inner end of the spring.

Figure 6 is a perspective view showing the end of the shaft and a cap or collar for the inner end of the spring, these parts being of modified construction.

Figure 7 is a fragmentary front to rear vertical sectional view through the spring housing and associated parts and showing the same modified construction as Fig. 6.

Figures 6 and 7 are on an enlarged scale.

The general construction of the typewriting machine can be of any suitable sort, my invention being applicable to such machines generally. In the drawing I have 70 shown a frame part 1, this being in the nature of an upper cross bar of the main frame of the typewriter, the forward part of the cross bar being shaped into a stationary rail 2 grooved for the reception of bearing 75 balls 3 which co-operate with a carriage 4, a fragment of which is conventionally shown. Said carriage comprises a longitudinal bar which may have ball bearing grooves in its opposite edges and which is 80 here shown set at an inclination of about 45°. As far as my invention is concerned, however, both the frame and the carriage can be of any suitable construction.

The main spring mechanism or assembly 85 is made as a detachable unit. It is all supported by a hanger or bracket 5, consisting of a bar of sheet metal bent into an inverted U-shape and detachably secured to the underside of the cross bar 1 by means of two 90 screws 6. The spring drum and all of its associated parts are mounted on this hanger and are put on to the machine and taken off as a unit by means of the screws 6.

The rotary part of the spring mechanism 95 includes a shaft 7 having a long bearing. Said shaft is here shown as made of reduced diameter at its middle part, its full-sized ends being journaled in a tube or sleeve 8 inserted in round holes in the depending 100 arms of the hanger 5. The general construction is such that this sleeve does not need to be tight in the hanger but it is held against endwise motion toward the rear by means of a collar 10 and set screw 11. A 105 motion of it toward the front of the machine is prevented by other parts of the mechanism as will hereafter appear.

The shaft 7 has a band wheel or drum 12 rigidly mounted on its forward end. As 110

here shown the wheel 12 has a hub 13 fitting on a reduced part of the shaft and said shaft is squared at 14 and passes through a hole of similar shape in the end of the hub 13 whereby said hub is prevented from turning on the shaft. The extreme end 15 of the shaft is reduced and threaded and a nut 16 holds the hub 13 in place. Said hub has a flange to which the wheel or drum 12 is riveted at 17. Any suitable hook 18, Fig. 1, may be connected with the carriage 4, and said hook may be connected with the wheel 12 by any suitable band or strap 20. In the present instance and preferably this band is connected with the wheel through a certain locking device which will be fully described hereinafter.

The sleeve 8 projects a short distance to the rear of the rear branch of the hanger 5, the projecting end of the sleeve being turned down to a reduced diameter as indicated in Fig. 3 and on said reduced end of the sleeve there are mounted a spring drum, box or housing 21, a washer 22, and a ratchet wheel 23, this group of parts being all secured together as by rivets 24. These three parts thus riveted together into one can be tightly mounted on the end of the sleeve, if desired, but this is not necessary. The ratchet wheel 23 is engaged by any suitable anchor pawl or detent 25, the one here shown being pivoted on a shouldered and headed screw 26 screwed into the hanger 5. This detent is of ordinary construction and mode of operation, being adapted to click over the teeth of the ratchet when said ratchet is turned in one direction and adapted to let the ratchet turn in the other direction tooth by tooth when the detent 25 is oscillated by hand.

For some of the purposes of my invention the driving spring can be mounted in the drum 21, with its outer end connected with the convex part 27 of said drum and its inner end with the shaft 7. With such a construction the spring could be put under tension by turning the drum 21 and the tension would be retained by the detent 25 and the power of the spring would be communicated through the shaft 7 to the band wheel 12. I have, however, shown an improved construction which makes the removal of the spring and its replacement by a new one extremely easy and convenient. To this end the spring 28 is not connected directly with the drum 21 but is mounted in a detachable device or cage 30. This cage can of course be variously constructed but the form of it shown in the drawings is a good and convenient one for my purposes. It consists of a piece of sheet metal cut out originally with a series of radially projecting arms 31 and said arms then bent back perpendicularly to the plane of the metal so as to constitute a sort of drum or cage or container for the spring. The spring can be coiled up and in-

serted in this cage, its outer end being connected with one of the arms 31 in any suitable manner. As here shown the end of the spring is simply bent double and hooked over one or two of said arms. This cage is very inexpensive and light and it is contemplated that the springs when manufactured shall each be mounted in one of these cages and kept in that way until it is desired to insert the spring either into a new machine or to replace an old spring in a used machine. The cage 30 itself is simply inserted into or is attached to the drum or wheel 21. The means shown in the drawings for this purpose are extremely simple and convenient. Three of the arms 31 are prolonged and each is cut out into a hook 32 and three slots 33 are cut in the web of the wheel 21. The cage is inserted into the drum with the projections 32 extending into the slots 33 and the cage is then slightly turned toward the left whereupon the slots 34 in the hooks 32 interlock with the web of the wheel 21 and positively retain the cage in place. The slots 34 are all cut in such a direction that when the spring is put under tension the pressure of said spring tends to hold the cage in its interlocking engagement with the drum. The web of the cage 30 may have cut-outs 29 for the fingers of the operator to facilitate insertion and removal of the cage.

The inner end of the spring can be connected with the shaft 7 in a variety of ways. Said shaft is here shown provided with a permanent bushing 35 slipped over its rear end and secured in place by means of a pin 36 one end of which pin in Figs. 1-5 projects beyond the bushing 35. Said bushing is made of such thickness as that it overlaps the drum 21 thus retaining said drum on the end of the sleeve 8 and preventing motion both of the shaft 7 toward the front of the machine and of said sleeve toward the rear of the machine, once the mechanism is assembled. In the form of the invention shown in Figs. 1-5 the inner end of the spring 28 is connected in any ordinary way with a collar 37, Fig. 5. As here shown said collar is formed with a hook 38 adapted to enter a hole in the inner end of the spring and to interlock with it in a familiar manner. The collar 37 has a longitudinal slot 40 and said collar is of such diameter that it can be slipped over the bushing 35 and the slot 40 will embrace the projecting end of the pin 36. Preferably the hole 41 at the center of the cage 30 is of a diameter only slightly greater than the bushing 35 and less than the external diameter of the collar 37. As the cage is positively held in place it prevents said collar 37 from slipping off.

From the above description it will be perceived that the spring, assembled as it is in its cage 30, can be almost instantly attached

to the machine by simply putting said cage in place with the collar 37 on to the bushing 35 and slightly turning the cage toward the left. It will also be perceived that as soon as this is done the spring can very easily be put under tension by turning the drum 21 toward the right until the desired tension is secured. It will also be readily understood that whereas I have shown the so-called drum or housing 21 in the form of a drum having a cylindrical part 27 that said cylindrical part is not absolutely essential. It gives the machine a more pleasing appearance, protects the spring to some extent and is a pleasanter thing to take hold of to put the spring under tension.

It will also readily be perceived that the hooks 32 could be made on the drum or wheel 21 and the slots 33 or some equivalent device in the cage 30. It will also be understood that, as far as the removable cage 30 is concerned, it is immaterial whether the drum 21 is stationary and the shaft 7 turns, or the reverse. The mechanism can be taken apart by removing the nut 16 and wheel 12, loosening the set screw 11, and drawing the sleeve 8 out of the hanger. When the cage 30 is removed, the shaft 7 can be withdrawn from the sleeve 8, and the drum 21 and its ratchet 23 can then be slipped off from the end of the sleeve.

In Figs. 6 and 7 I have shown a modified form of connection from the inner end of the spring to the shaft 7. As this shaft is slightly modified in shape in these figures I have called it 7^a. In this form of the invention the majority of parts including the cage 30 are or may be identical with those shown in the other figures but the bushing 35^a is shorter than the bushing 35 and the pin 36^a does not project beyond said bushing. On the other hand the end of the shaft 7^a is squared as shown at 42. In place of the collar 37 a collar or cap 43 is provided which fits over the bushing 35^a and is formed with any suitable stud or hook 44 to interlock with the inner end of the spring. The rear end of said cap is closed and the end thereof has a square opening 45 cut out to fit the squared end 42 of the shaft. This form of the invention is somewhat more convenient than the other in this respect that the operator can see through the hole 45 and can thus somewhat more readily turn the drum and spring until said hole matches with the squared end 42 in the act of putting the spring in place. Neither of the collars 37 and 43 is absolutely essential as the inner end of the spring could interlock directly with the shaft 7 or bushing 35 and pin 36 if desired.

A lock or detent to prevent unwinding of the spring under certain conditions has been provided as hereinbefore mentioned. Detail 65 construction of this lock can be varied but I

prefer the form here shown. A stationary ratchet wheel 46, Figs. 1 and 3, surrounds the inner end of the hub 13, preferably without touching said hub, and it is secured to the forward face of the bracket 5 by rivets 70 47, a washer 48 being preferably interposed to space the stationary ratchet wheel slightly away from the bracket. A pawl 50 of bell crank form is pivoted to the web of the band wheel 12 in position to engage the 75 ratchet 46 and so that when it does engage said ratchet the band wheel is locked against turning in a direction to unwind the main spring. As here shown, a hollow stud 51 projects rearward from the web of the wheel 80 12 to which it is "staked" or riveted. A pivot 52 is similarly secured to the front face of the pawl 50 and projects through the hollow stud 51 and a screw 53 with a broad head screwed lengthwise into said 85 pivot 52 prevents said pivot from moving rearward out of its bearing. The pawl 50 has an arm 54 extending radially outward from the pivot 52, and about in the plane of the cylindrical part of the wheel 12 this 90 arm is bent at right angles forming a sort of arm or lug 55 lying substantially in the cylindrical surface of the wheel 12. The cylindrical part of this wheel is cut away to accommodate the pawl as shown in Fig. 1 95 forming two shoulders 56 and 57 which limit the rocking motion of the pawl about its pivot 52. The strap 20 has a loop on its end which is hooked over the lug 55 so that the said strap is connected with the wheel 100 12 through the pawl; and when the parts are under tension as shown in full lines in Fig. 1 the pull on said strap holds the pawl up against this shoulder 57 and out of engagement with the ratchet 46. A spring 58 connected at one end to a pin 60 on the pawl 50 and at the other end to a pin 61 on the wheel 12 tends to throw the pawl into engagement with the ratchet but as this spring is much weaker than the carriage 110 spring it is readily stretched by the latter and the pawl under normal conditions remains always in the position shown in Fig. 1 out of engagement with the ratchet 46. If, however, the strap 20 should break as indicated in broken lines in Fig. 1 the spring 58 would quickly draw the arm 54 back against the shoulder 56 and throw the pawl into the stationary ratchet as shown in broken lines and thus stop the unwinding of the main 115 spring. This would happen if the strap should accidentally slip off of the wheel, or if for any other reason the resistance due to the carriage were suddenly removed. Moreover, if at any time it was desired to unhook the strap from the carriage the operator by momentarily holding the wheel 12 against turning can let the pawl into the ratchet and thus lock the spring against unwinding. 120

Various changes may be made without de- 125

parting from my invention, and parts of the invention can be used without other parts.

What I claim as new and desire to secure by Letters Patent, is:—

- 5 1. In a typewriting machine, the combination with a carriage, a spring driven wheel and a strap by which said wheel propels said carriage, of a lock adapted to hold said wheel against turning to unwind 10 its spring, one element of said lock constituting the means whereby said strap is connected with said wheel and said strap normally holding said lock out of action.
- 15 2. In a typewriting machine, the combination with a carriage, a spring driven wheel and a connection from said wheel to propel said carriage, of a lock including a spring tending to bring said lock into action to prevent turning of said wheel in a 20 direction to unwind its spring, and means whereby the pull on said carriage connection holds said lock out of action against the pressure of its spring.
- 25 3. In a typewriting machine, the combination with a carriage, a spring driven wheel, and a connection from said wheel to propel said carriage, of a pawl and ratchet adapted to prevent unwinding of said wheel, and means whereby said carriage connection holds said pawl out of engagement with said ratchet.
- 35 4. In a typewriting machine, the combination with a carriage, a spring driven wheel and a connection from said wheel to 40 propel said carriage, of a pawl and ratchet, means whereby said carriage connection acts on said wheel through said pawl and holds said pawl out of engagement with said ratchet, and means for moving said pawl into engagement with said ratchet when the carriage connection is broken.
- 45 5. In a typewriting machine, the combination with a carriage, a spring driven wheel and a connection from said wheel to 50 propel said carriage, of a stationary ratchet, a pawl mounted on said wheel and tending to engage said ratchet to prevent unwinding of said spring, said carriage connection acting on said wheel through said pawl and normally holding said pawl out of action.
- 55 6. In a typewriting machine, the combination with a carriage, a spring driven wheel and a connection from said wheel to 60 propel said carriage, of a stationary ratchet, a pawl mounted on said wheel and having a spring tending to move into engagement with said ratchet, and a strap connected at one end with said pawl and at the other end with the carriage, the pull on said strap normally holding said pawl out of engagement with said ratchet.
- 65 7. In a typewriting machine, the combination with a carriage, of a drum and a shaft for said drum, said drum and shaft being relatively rotatable, a cage having a spring

therein, means for detachably connecting said cage with said drum, a collar to which the inner end of the spring is connected, a detachable connection between said collar and said shaft, the whole construction being 70 such that said cage with the spring and collar in it can be readily attached to and detached from said drum and shaft; and a connection between one of said drum and shaft elements and the carriage.

8. In a typewriting machine, the combination with a carriage, of a drum, a shaft on which said drum is rotatably mounted, a spring, a cage in which said spring is mounted and to which the outer end of the 80 spring is attached, a collar to which the inner end of the spring is attached, a detachable connection between said cage and drum, means for preventing relative turning motion between said collar and said shaft but 85 permitting the collar to be slipped lengthwise over the end of the shaft; and means connecting one of said drum and shaft elements to drive said carriage.

9. In a typewriting machine, the combination with a carriage, of a shaft, a carriage driving wheel on one end of said shaft and connected with the carriage, a drum rotatably mounted on the other end of said shaft, a spring having its outer end connected with said drum and its inner end connected with said shaft so that the spring 90 can be put under tension by turning said drum, and a detent for holding said drum when it has been turned to put the spring 95 under tension.

10. In a typewriting machine, the combination with a carriage, of a shaft having a wheel rigidly mounted on one end of said shaft and a drum loosely mounted on the 105 other end of said shaft, said wheel and drum spaced apart, and a long bearing for the shaft between the drums, the first mentioned drum being connected with the carriage, and the second mentioned drum having a 110 driving spring therein with its inner end connected with said shaft; and a detent for holding the last mentioned drum against backward rotation to maintain the tension on said spring.

11. In a typewriting machine, the combination with a main frame and a carriage, of a hanger detachably secured to said main frame, a sleeve mounted in said hanger, a shaft journaled in said sleeve, a drive wheel 115 fast on one end of said shaft and connected with said carriage, and a driving spring connected with the opposite end of said shaft.

12. In a typewriting machine, the combination with a main frame and a carriage, of a U-shaped hanger detachably secured to said main frame, a sleeve mounted in the two arms of said U-shaped hanger, a shaft journaled in said sleeve, a drive wheel on one end of said shaft and connected with 125 130

said carriage, and a driving spring connected with the other end of said shaft.

13. In a typewriting machine, the combination with a main frame and a carriage, of 5 a U-shaped hanger detachably secured to said main frame, a sleeve mounted in the two arms of said hanger, a shaft journaled in said sleeve, a drive wheel on one end of said shaft and connected with said carriage, a spring drum mounted on the opposite end of said sleeve, and a spring in said drum having its inner end connected with said shaft.
14. In a typewriting machine, the combination with a carriage, of a sleeve, a drum 15 mounted on said sleeve, a spring in said drum and having its outer end connected with said drum, a shaft journaled in said sleeve and having the inner end of said 20 spring connected therewith, driving connections from said shaft to said carriage, and a detent for said drum, the construction being such that said spring can be tensioned by turning said drum by hand.

15. In a typewriting machine, the combination with the carriage of the machine, of a driving spring for said carriage, a shaft having a polygonal end, a cup-shaped device to which the inner end of said spring is attached, said device being adapted to be 25 slipped over the end of said shaft and having in its bottom a hole adapted to the polygonal end of said shaft; and means connecting one of said drum and shaft elements to drive said carriage.

16. In a typewriting machine, a carriage strap adapted to rotate a driving drum through a pawl, which pawl if the strap should break, is adapted to arrest the drum.

Signed at the borough of Manhattan, city 40 of New York, in the county of New York and State of New York this 5th day of March, A. D. 1920.
